UNITED STATES PATENT OFFICE.

WALTER GREIG, OF NIAGARA FALLS, NEW YORK, ASSIGNOR TO AMERICAN SALES BOOK COMPANY, LIMITED, OF TORONTO, ONTARIO, CANADA, A CORPORATION OF ONTARIO.

MANIFOLDING PAD.

Application filed November 18, 1924. Serial No. 750,517.

This invention relates to manifolding devices and with respect to its more specific features to a supply pad, or book, for use in manifolding machines, autographic registers and the like.

Objects of the invention are to provide a practical device of the character referred to wherein registration of the leaves for manifolding inscription is improved; wherein the operation of manifolding is facilitated especially after partly inscribed leaves are removed from the machine, and wherein the handling of a pad having assembled carbon coated leaves, without soiling the fingers, is much improved.

Other objects of the invention will be in part obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawing, in which:

Figure 1 is a diagrammatic perspective view of a portion of the pad, or book, the strips being spread out for clearer illustration,

Fig. 2 is a top plan view of a length of one of the strips, certain adhesive spots on the bottom being shown by the dotted areas, and

Fig. 3 is a diagrammatic perspective view of the pad.

Referring now more specifically to the drawing, Fig. 1 illustrates three record strips, each folded zigzag, the fold lines being indicated at 1, 2 and 3 respectively. It will be seen that the folds of one strip are closely interengaged with those of the others so as to provide a plurality of sets of leaves 4, 5 and 6, the leaves of each set being in superposed manifolding relation to each other and the several sets being in superposed contiguous relation to each other, when in pad or book form, as illustrated in Fig. 3. One of the leaves of each manifolding set is embodied in one of the

strips, so that such leaves are connected end to end. For instance, all the leaves 4 are in the same strip, and are connected at the fold lines of the strips.

The invention has specially in view adaptation for the feeding of the associated strips in a manifolding machine, the strips themselves having apertures for cooperation with the feed mechanism of the machine to promote accurate registration of the leaves of each manifolding set. A type of feeding and registering mechanism with which the pad of this invention is especially adapted to cooperate is disclosed in the patent to L. F. Hagemann, No. 1,456,773, patented May 29, 1923. For the purpose of cooperating with said mechanism, the strips herein referred to are each provided with form-registering apertures, as at 7, 8 and 9, preferably two apertures being provided in each strip, symmetrical with respect to the central longitudinal line of the strip and to one side of each fold line, these apertures being also preferably between the successive printed forms 10 in each strip, which forms, as will be understood, are in longitudinal series in each strip. The form registering apertures in each leaf of a manifolding set of leaves are in the same fixed relation to the printed forms on these leaves so that when the apertures of these superposed leaves register with each other, the printed forms on these apertured leaves will also be in registry and ready for inscription and accurate manifolding.

It will be noted that the manifolding sets are composed of the separate independent strips hereinbefore referred to, there being three separate strips illustrated, providing three leaves in each set, although a greater number of strips may be employed. The superposed and interfolded arrangement of the strips tends to restrain the respective leaves of either of the manifolding sets from relative movement out of registering relation, not only when in close superposed relation in the pad, or book, but when the strips are drawn from the pad by the action of the feed mechanism hereinbefore mentioned.

To further promote retention of registration, in the book and in the machine, and after inscribed sets have been removed from the machine (as by being parted at the fold

lines), one or more of the strips is caused more or less to adhere to an adjacent strip. In the embodiment illustrated the adherence is effected by providing the under face of the two uppermost leaves of each manifolding set with a spot of adhesive, which spot lies in contact with the upper face of the next underlying leaf of the same set. In the form illustrated, these spots are indicated at 11 and 12 respectively, being on the under faces of two of the leaves of each manifolding set and being directly beneath or in registration with some part of the printed forms. The adhering effect of the spot, before mentioned, should not be sufficient absolutely to prevent relative sliding movement between the leaves under the pull of the feed mechanism of the machine when such relative movement is necessary to effect registration. Slight adherence will answer and it is found that the adhering qualities pertaining to the usual carbon transfer material are sufficient. Transfer material being of a variety of consistencies, a quality should be selected which does not smut readily and which is not too soft, in order to obtain the best practical results. By coating the under faces of the leaves with the transfer material in spots, as distinguished from over all, sufficient adherence for operatively retaining registration is obtained, and yet, because of the area of the spot being restricted in size, the adherence is not so great as to prevent relief of the adhering effect and relative movement, by the feeding and registering mechanism of the machine, between those leaves which immediately coact with said mechanism.

For facilitating the separation of one manifolding set from an adjacent set, the fold lines 1, 2 and 3 are weakened, as by being perforated, and it will be noted that the spots hereinbefore referred to occur on one or more leaves of each manifolding set, so that when any set is torn off, even after inscription in the machine, it is still in a condition for subsequent manifold inscription within the spotted area.

In order to facilitate the advance of the manifolding sets through the machine, the under or outer face 13 of the lowermost leaf of each of the manifolding sets is left clean and unspotted, so as to move smoothly over the platen of the machine without substantial adherence thereto and so as to avoid soiling the platen and impairment of subsequent records. Not only are the lowermost faces of the manifolding sets clean, but the upper, or outer, faces are also clean, the transfer material being confined to between the leaves, so that the three associated leaves or the three associated strips may readily be handled without soiling the fingers with the carbon transfer material. Furthermore the spotted leaves may also be readily handled

without soiling the fingers because the spots of transfer material cover but a portion of the area of the leaves, thereby leaving a large and clean margin on each leaf. The arrangement whereby either the connected leaves forming the strips or the leaves of the separate sets may readily be handled without soiling the fingers, is of much value even aside from the adhering feature of the transfer material. Hence, viewed in this aspect, the invention contemplates the use of transfer material independent of its adhering quality.

In practice each of the several strips is provided with a longitudinal series of the similar printed forms 10, these forms being pertinent to the transaction of which record is to be made. An ordinary bill form has been illustrated. The strips are then folded and assembled in the manner hereinbefore described and as more particularly appears diagrammatically in Fig. 1, to form a flat pad as diagrammatically illustrated in Fig. 3. The topmost set of leaves of this pad may readily be applied to the feeding and registering mechanism of the machine in conjunction with which the record is to be made, whereupon actuation of the feed mechanism will advance the sets of leaves in a serial manner, one set after the other being drawn over the platen into position for inscription. The leaves of each manifolding set in the pad are originally disposed in such manner that the forms and apertures thereof are in as close registry as possible. The close association of the interfolded strips in the pad tends to maintain this registry, and when the sets are drawn from the pad the associated bends of the strips also tend to maintain the registry and to restrain relative movement between the advancing leaves of a manifolding set. The spots of adhesive transfer material also tend to restrain relative movement between the leaves and at the same time provide areas in each set whereon manifolding inscription may be effected. Should manifold inscription be desired in unspotted areas on the leaves, the separate carbon transfer leaves of the machine may be utilized for the purpose. After inscription in the machine, whether by hand or by instrumentalities which may be provided in the machine, the inscribed set may be severed from the next succeeding set along the weakened lines intermediate the two sets. Manifolding inscription may be made on this torn-off set within the spotted area and without the use of additional transfer leaves. Furthermore it will be noted that the spotted areas are illustrated as longitudinally in line with the form registering apertures 7 so that the feed disks of the feed mechanism hereinbefore referred to will operate to press the leaves together across the spotted areas as the inscribed set is discharged from the

machine, preparatory to being torn off. In this wise, should the adherence due to the spots have been overcome by the machine in its operation of registering the set, the subsequent pressure of the feed mechanism tends to restore the adhering effect at the spots, so that the leaves of the torn off set may again be caused to adhere at the spotted areas. Subsequent manifold inscription of the torn set may then be made with the leaves in registry as before.

Since certain changes may be made in the above article and different embodiments of the invention could be made without departing from the scope thereof, it is intended that all matter contained in the above description or shown in the accompanying drawing shall be interpreted as illustrative and not in a limiting sense.

Having described my invention what I claim as new and desire to secure by Letters Patent is:—

1. A supply pad for manifolding machines, said pad including, in combination, two relatively superposed record strips folded zig-zag, the folds of one interengaged with those of the other so as to provide superposed manifolding sets of superposed leaves connected end-to-end, each strip having a longitudinal series of printed forms and a series of form-registering apertures in fixed relation to said forms, respectively, one of the leaves of each of said sets having an adhesive spot of transfer material in adhesive contact with the face of the other leaf of the set, the outer face of each of the two strips being unspotted.

2. A supply pad for manifolding machines, said pad including, in combination, two relatively superposed record strips folded zig-zag, the folds of one interengaged with those of the other so as to provide superposed manifolding sets of superposed

leaves connected end-to-end, each strip having a longitudinal series of printed forms and a series of form-registering apertures in fixed relation to said forms, respectively, one of the leaves of each of said sets having a relatively small spot of transfer material in contact with the face of the other leaf of the set, said spot covering a portion only of such leaf, the remainder of such leaf being uncoated, and said spots being in longitudinal alignment with said apertures.

3. A supply pad for manifolding machines, said pad including, in combination, two relatively superposed record strips folded zig-zag, the folds of one interengaged with those of the other so as to provide superposed manifolding sets of superposed leaves connected end-to-end, each strip having a longitudinal series of printed forms and a series of form-registering apertures in fixed relation to said forms, respectively, one of the leaves of each of said sets having a relatively small adhesive spot of transfer material in adhesive contact with the face of the other leaf of the set, said spot covering a portion only of such leaf, the remainder of such leaf being uncoated, and said spots being in longitudinal alignment with said apertures.

4. A supply pad for manifolding machines, said pad including, in combination, two separate record strips folded zig-zag, the folds of one interengaged with those of the other so as to provide superposed sets of superposed leaves connected end-to-end, each strip having a longitudinal series of printed forms, successive sets of superposed leaves having, between the leaves thereof, an isolated spot of transfer material of an adherent character.

In testimony whereof I affix my signature.

WALTER GREIG.
